UNITED STATES PATENT OFFICE

138,515

DESIGN FOR A COMBINED WRENCH AND SPANNER

Otto Hardy, Ventura, Calif.

Application April 17, 1944, Serial No. 113,286

Term of patent 7 years

(Cl. D54—16)

To all whom it may concern:

Be it known that I, Otto Hardy, a citizen of the United States, residing at Ventura, in the county of Ventura and State of California, have invented a new, original, and ornamental Design for a Combined Wrench and Spanner of which the following is a specification, reference being had to the accompanying drawing, forming part thereof.

Figure 1 is a side elevational view of a com-

bined wrench and spanner showing my new design.

Figure 2 is an edge elevational view.

Figure 3 is a view showing the opposite edge of the combined wrench and spanner in elevation.

I claim:

The ornamental design for a combined wrench and spanner as shown.

OTTO HARDY.
